*Primary Examiner—M. N. Pandozzi**Attorney, Agent, or Firm—Norris, McLaughlin & Marcus*[57] **CLAIM**

We claim the ornamental design for a bowl, as shown and described.

DESCRIPTION

FIG. 1 is a perspective view of the bowl of the present invention showing the open end, side and ribbed portions; FIG. 2 is a side elevational view thereof;

FIG. 3 is a bottom plan view thereof;

FIG. 4 is a top plan view thereof showing the inside of the bowl from the open end; and,

FIG. 5 is a cross sectional view taken along line 5—5 of FIG. 4.
